Inventor:

Samuel S. Colt

UNITED STATES PATENT OFFICE.

SAMUEL S. COLT, OF ORANGE, NEW JERSEY.

COMBINED BEVEL, MITER, AND TRY-SQUARE.

SPECIFICATION forming part of Letters Patent No. 330,378, dated November 17, 1885.

Application filed August 15, 1885. Serial No. 174,466. (No model.)

To all whom it may concern:

Be it known that I, SAMUEL S. COLT, a citizen of the United States, residing at Orange, in the county of Essex and State of New Jersey, have invented a new and useful Improvement in a Combined Bevel, Miter, and Try-Square, of which the following is a full, clear, and exact description.

The object of my improvement is to provide a simple, useful, and effective instrument for artisans and others, which may be used either as a bevel and miter or try-square.

My improvements consist of the arrangement of the scales; the mode of indicating the position of the blades with their respective scales, the device for clamping and pivoting the blades, and the arrangement of the miter-blade, when not in use for bisecting angles, as a try-square.

Figure 1 represents a plan view in perspective of an instrument with my improvements. Figs. 2, 3, 4, 5, 6, 7, 8, 9, 10, and 11 represent details of construction.

Similar letters refer to similar parts throughout the several views.

In Fig. 1, A and A' represent the body or handle, and is constructed into two separate parts, as represented in Figs. 2 and 3, Fig. 2 being the view on edge of piece A, showing the scale which represents the movement of the slotted blade B, and is laid out in spaces representing degrees, marked to correspond, and graduated to one hundred and eighty degrees. In Fig. 3, A' is likewise a view on edge, (rear front,) showing the scale which represents the movement of the miter-blade C, and is laid out in spaces representing degrees, marked to correspond, and graduated to ninety degrees. The slotted blade B has within the

slot a guide, c, rectangular in form, as shown in Fig. 5, and moves forward or backward therein. Extending from each side are two studs, a and b. The stud a is turned perfectly true, and is fitted to the flanged sleeve, Fig. 4, which is shown in position on piece A', Fig. 3, in dotted lines. This forms the pivot and bearing for blade B. The end of this stud is riveted at the flange, and fills the countersink. The stud b is also turned true,

and has a thread formed thereon, and receives a thumb-nut, Fig. 7, which forms the clamping device. c' is a line running longitudinally through the center of the blade B and the guide c, and forms an index to indi-

cate the movement of the blade B with its scale. The miter-blade C rotates on a fixed pivot, which is formed of a plain stud, Fig. 11. One end has a thread formed on it, and is screwed in the metal piece, Fig. 9, and the end riveted to fill the countersink. The opposite end has also a thread formed on and receives a thumb-nut, Fig. 7, which forms the clamping device for blade C. A line, d, marked through the center of blade C, running longitudinally therewith, forms an index to indicate the movement of the blade with its scale.

Figs. 6 and 8 represent two washers, the former being placed on the stud of blade B and on one side of that blade, and the latter on the stud of blade C and on the other side of that blade, so that both blades may fold within the body or handle.

Fig. 9 is a metal piece, which is fitted to back of body-piece A', as shown, and has two holes drilled and tapped to receive two screws, one of which is shown in Fig. 10. The blade C has two slotted openings, (not shown,) in which these screws fit, the object being to hold the blade stationary when at right angles with the body or handle A and A', for use as a try-square when not required for bisecting angles.

In Fig. 1 body-pieces A, e, and e' are two metal sleeves or bushings, which the studs forming the clamping device pass through, and are to protect the piece A, when made of wood, from wear.

The scales are shown separate on the body-pieces A and A', and I do not confine myself in the operation of the instrument strictly thereto, as the two scales can be laid out on one piece.

Having fully described my invention, what I claim as new, and desire to secure by Letters Patent, is—

A bevel composed of the body or handle A and A', slotted blade B, miter-blade C, indexes c' and d of blades B and C, the scales formed on edge of body or handle A and A', the guide c, with pivot and clamping device for securing blade B, the clamping device for securing blade C, and the device for holding blade C stationary for use as a try-square, all substantially as set forth.

Witnesses: SAMUEL S. COLT.

JNO. H. IMMEN,
THOMAS CANNODY.
